H. P. WICKERSHAM

WELL DRILLING BIT

Filed June 9, 1924

Fig. 3. Fig. 4.

Inventor
Harry P. Wickersham

by *W. H. Maxwell*
his Attorney

UNITED STATES PATENT OFFICE.

HARRY P. WICKERSHAM, OF WALNUT PARK, CALIFORNIA.

WELL-DRILLING BIT.

Application filed June 9, 1924. Serial No. 718,849.

to all whom it may concern.

Be it known that I, HARRY P. WICKERSHAM, a citizen of the United States, resident of Walnut Park, county of Los Angeles, State of California, have invented new and useful Improvements in Well-Drilling Bits, of which the following is a full, clear, and accurate description.

This invention has to do with a well drilling bit, and it is an object of the invention to provide a bit which is simple and effective.

This invention is particularly applicable to disk and roller bits, and has particular reference to a disk or roller mounting. Throughout this application reference will be had to a bit of the disk type, and I will describe a form of mounting embodying the present invention particularly suited for a disk; it being understood that such reference is had for purpose of facilitating a full and accurate understanding of the invention, and is not intended to limit or restrict the scope of the invention to such specific application.

An object of this invention is to provide a mounting for a disk, or the like, which is simple, effective and secure.

Another object of the invention is to provide a mounting of the character specified, which is compact and does not present projecting or protruding parts apt to be injured or to interfere with the operation of the bit.

Another object of this invention is to provide a mounting of the character specified, which is simple, quick and convenient to manipulate.

The various objects and features of this invention will be best and more fully understood from the following detailed description of a typical form and application of the invention throughout which description reference is had to the accompanying drawings in which

Fig. 1 is a side elevation of a simple form or bit of the disk type embodying the present invention.

Fig. 2 is a view of the bit shown in Fig. 1 taken as indicated by line 2—2 on Fig. 1.

Fig. 3 is an enlarged detailed sectional view of the mounting provided by this invention being a view taken as indicated by line 3—3 on Fig. 1, and

Fig. 4 is a view showing a wrench suitable

for use in operating the construction provided by this invention.

The bit illustrated in the drawings is a simple and typical form and type of bit to which the present invention can be advantageously applied. It comprises, generally, a body 10 and disk cutters 11 carried at the lower end of the body so that they project therefrom, and will operate to cut a hole when the bit is rotated. The body 10 is of a general form and construction common to bits of this general character, and includes a tapered screw threaded shank 12 at its upper end, and a plurality of downwardly extending legs or projections 13 and 14 at its lower end. The shank 12 is provided on the body for mounting it on or connecting it to a suitable string of drill pipe, or the like. The projections 13 and 14 are for the purpose of carrying the disk 11, and in the present form of bit, where there are two disks, there is a center projection 13, and outer projections 14 at opposite sides of the center projection 13. The general arrangement and relationing of the projections is clearly illustrated in Figs. 1 and 2 of the drawing. It is to be noted that the outer projections 14 in addition to being at opposite sides of the center projection 13 are staggered or off-set relative to each other.

The disk cutters 11, which may be constructed and shaped in various manners, are arranged between the projections 13 and 14 and are rotatably carried on pins 15. The pins 15 extend between and are carried by the projections 13 and 14.

In accordance with this invention each mounting pin 15 is provided at one end with screw threads 16 and at the other end with an enlargement or head 17. The screw threaded end of the pin 15 is adapted to screw thread into the opening so that the head 17 seats in the bottom of the enlarged outer portion 19 of an opening 20 formed through the other projection. In the present case I have illustrated the opening 18, in the center projection 13 and have shown it extending completely through the projection. The opening 20 is in the other or outer projection and its enlarged outer portion 19 is made to more or less accurately fit or carry the head and portion of the pin in the manner clearly illustrated in Fig. 3. The head 17 of the pin is round to fit the

portion 19 of the opening 20, and is preferably made comparatively thin, consistent with strength and durability, so that it occupies only the bottom or inner part of the portion 19. The pin 15 is arranged in and removed from position through the opening 20 and is provided at either or both ends with means whereby it can be engaged for the purpose of rotating it to screw it into 10 and out of the opening 18. In practice this means may be in the form of an irregular or polygonal socket 21 shown in the drawings in the threaded end of the pin. The enlarged outer portion 19 of the opening 20 is screw threaded and a lock bolt 22 is provided to screw thread into it over the head 17 of the pin. The plug 22 is adapted to be tightened into the portion 19 so that it bears or clamps tightly on the head 17 to 15 lock or secure the pin in place. The plug may, in practice, be made sufficiently thin to be completely carried in the portion 19 when in place to lock the pin. With this arrangement it is necessary to provide the 20 plug with means whereby it can be engaged for purpose of operating it. This means may comprise an irregular or polygonal socket 24 in the outer end of the plug. In practice the screw threads in the opening 18 and those in the portion 19 of the opening 20 may be opposite, that is, in one case left-handed and the other case right-handed thus further preventing the possibility of the mounting becoming loose.

35 The present invention further provides means for preventing rotation between the plug and pin so that the pin cannot work loose. In its preferred form this means includes a bolt or plunger 40 carried by the pin to cooperate with an opening 41 in the plug. The plunger 40 is noncircular in cross sectional configuration and is provided at its inner end with a head 42. The plunger is carried in a recess 43 in the head end of the 40 pin and is retained in the recess and held against rotation by a retaining member 44 fixed in the outer part of the recess. A spring 45 is arranged in the recess behind the plunger to normally hold it in an out 45 position where its outer end projects from the head of the pin. The opening 41 in the plug is shaped to correspond to the plunger and is located to receive the plunger as shown in Fig. 3. The opening 41 extends 50 through the plug and opens into the socket 24. When the plunger is in the opening in the plug the pin and plug are locked together against relative rotation. When the plug is being arranged in or removed from the portion 19 of the opening 20 the plunger is depressed. In practice a wrench such as is shown in Fig. 4 can be advantageously used for this purpose. This wrench has a head 50 adapted to fit the socket in the plug and has a projection 51 adapted to extend

into the opening 41 to displace the plunger therefrom.

The disk 11 is provided with a central opening 25 to receive or pass the pin 15 so that the disk is rotatable on the pin. In practice it is desirable to provide suitable washers 26 on the pin at either side of the disk in a manner such as is illustrated in Fig. 3 of the drawings. The washers operate to take the wear that comes upon the 75 parts and to properly space the disk in the body.

To mount the disk 11 it is arranged in position between the projections and the pin 15 is arranged in place between the projections and through the disk through the opening 20. When the pin has been tightly screw threaded into the opening 18 the plug 22 is tightened against the head 17 locking the pin so that the bit is ready for operation. 80 To remove the disk it is merely necessary to remove the plug 22, and then the pin 15.

It is to be particularly noted that I have by my present invention provided a mounting suitable for a disk, a roller, or like device, which is extremely simple, inexpensive, strong and durable, and is convenient and simple to manipulate. I have further provided a mounting which is particularly compact, and in which there are no parts protruding or projecting in a manner to become worn through operation of the bit, to become broken off, or to interfere with proper circulation or operation of the bit, etc.

Having described only a typical preferred 100 form of my invention, I do not wish to limit myself to the specific details hereinabove set forth but wish to reserve to myself any changes or variations that may appear to those skilled in the art or fall within the 105 scope of the following claims.

Having described a preferred form of my invention, I claim:

1. In a bit having two spaced parts with 110 openings at opposite points, a cutting member, and a pin for mounting the cutting member between said parts, the pin being arranged to extend between the parts and having one end screw threaded into the opening in one part, a head on the other end of the pin completely carried in the opening in the other part, and a plug screw 115 threaded into said last mentioned opening over the head of the pin.

2. In a bit having two spaced parts having 120 openings at opposite points, a cutting member, and a pin for mounting the cutting member between said parts, the pin extending between the parts and having one end screw threaded into the opening in one of 125 said parts, a shoulder in the opening in the other of said parts, a head on the pin carried in the last mentioned opening against the shoulder, and a plug screw threaded in the last mentioned opening over the head. 130

3. In a bit having two spaced parts with openings at opposite points, a cutting member, and a pin for mounting the cutting member between said parts, screw threads on the pin to engage the opening in one part, a head on the other end of the pin completely carried in the opening in the other part a plug screw threaded into the last mentioned opening over the head, the threads on the pin and plug being opposite.
4. In a bit having two spaced parts with openings at opposite points, a cutting member, and a pin for mounting the cutting member between said parts, the pin being arranged to extend between the parts, screw threads on one end of the pin to engage the opening in one part, a head on the other end of the pin completely carried in the opening in the other part, and a plug screw threaded into said last mentioned opening over the head of the pin, the ends of the pin and the plug being completely within said parts.
5. In a bit having two spaced parts with openings at opposite points, a cutting member, and a pin for mounting the cutting member between said parts, the pin being arranged to extend between the parts and having one end screw threaded into the opening in one part and having a head on its other end completely carried in the opening in the other part, a plug screw threaded into said last mentioned opening over the head of the pin, and means at the screw threaded end of the pin and the outer end of the plug whereby they can be engaged for rotation.
6. In a bit having two spaced parts with openings at opposite points, and a cutting member, a pin for mounting the cutting member between said parts, the pin being arranged to extend between the parts and having one end screw threaded into the opening in one part and having a head on its other end completely carried in the opening in the other part, and a plug screw threaded into said last mentioned opening over the head of the pin, and means for preventing relative rotation between the plug and pin.
7. In a bit having two spaced parts with openings at opposite points, a cutting member, and a pin for mounting the cutting member between said parts, the pin being arranged to extend between the parts one end of the pin to engage the opening in one part, and, a plug screw threaded in the opening in the other part over the pin, the threads on the pin and plug being of different pitch.
8. In a bit having two spaced parts with openings at opposite points, a cutting member, and a pin for mounting the cutting member between said parts, the pin being arranged to extend between the parts and having one end screw threaded into the opening in one part having a head on its other end completely carried in the opening in the other part, and a plug screw threaded into said last mentioned opening over the head of the pin, and a releasable connection between the pin and plug to prevent relative rotation between them.
9. In a bit having two spaced parts with openings at opposite points, a cutting member, and a pin for mounting the cutting member between said parts, the pin being arranged to extend between the parts and having one end screw threaded into the opening in one part and having a head on its other end completely carried in the opening in the other part, a plug screw threaded into said last mentioned opening over the head of the pin, the plug having an opening through it, and a releasable connection between the pin and plug preventing relative rotation between them and operable through the opening in the plug.
10. In a bit having two spaced parts with openings at opposite points, a cutting member, and a pin for mounting the cutting member between said parts, the pin being arranged to extend between the parts and having one end screw threaded into the opening in one part and having a head on its other end completely carried in the opening in the other part, a plug screw threaded into said last mentioned opening over the head of the pin, the plug having an opening through it, and a plunger normally yieldingly extending from the pin to cooperate with the opening in the plug to prevent relative rotation between the pin and plug.

In witness that I claim the foregoing I have hereunto subscribed my name this second day of June 1924.

HARRY P. WICKERSHAM.
